(74) Attorney, Agent, or Firm — Alexander Chen, Esq.

(57) CLAIM

The ornamental design for an automobile front grille, as shown and described.

DESCRIPTION

FIG. 1 is a top and front perspective view of an automobile front grille showing my new design;

FIG. 2 is a front view thereof;

FIG. 3 is a left side view thereof;

FIG. 4 is a top view thereof; and,

FIG. 5 is a front and bottom perspective view thereof. The broken lines shown in the drawing views depict portions of the automobile front grille that are for environmental and illustrative purposes that form no part of the claimed design.
